UNITED STATES PATENT OFFICE.

AUBREY LEO McCAFFREY, OF NEW YORK, N. Y., AND JAMES G. MANNING, OF NEW BRUNSWICK, NEW JERSEY.

AEROPLANE.

1,413,749.

Specification of Letters Patent. Patented Apr. 25, 1922.

Application filed January 24, 1919. Serial No. 272,804.

To all whom it may concern:

Be it known that we, AUBREY LEO McCAFFREY and JAMES G. MANNING, citizens of the United States, residing, respectively, in New York city, in the county of Bronx and State of New York, and in New Brunswick, in the county of Middlesex and State of New Jersey, have invented certain new and useful Improvements in Aeroplanes, of which the following is a specification.

This invention relates to aeroplane flying-speed reduction in heavier-than-air aeroplanes, its object being to provide means under the control of the operator for setting up during landing movements a counter-force operative to slow down the forward travel of the aeroplane.

It is not safe during the landing movements of heavier-than-air aeroplanes to reverse the propeller or screw-carrying motor because of the time involved in stopping and starting the motor and the necessity of keeping the aeroplane at a flying speed during the glide to the landing, and until the flying speed has been sufficiently reduced to make it safe to land.

By our invention we enable the operator at will to reverse the propeller blade wash, thereby setting up a counter-force tending to slow down the forward travel of the aeroplane over and at its landing place, and to shorten the distance of its run over the ground. It is customary for landing, to descend at a flying speed frequently at the rate of ninety miles an hour, throttling the motor at a time deemed proper, down to idling speed, and finally effecting a landing. In all such landing movements as heretofore conducted, the blade wash has been rearwards as in flight during the forward travel of the aeroplane.

In the accompanying drawings forming a part hereof and illustrating the principle of this invention in the best mode now known to us of applying that principle,

Fig. 1 is a perspective showing a portion of an aeroplane; its propeller-carrying motor in tractor location; and our new propeller-blade-reversing mechanism. In this view the propeller blades are shown in position to send the blade wash rearwards for flying.

Fig. 2 is a plan of the shifter detached, and connected with a hand-controlled lever.

Fig. 3 is a side view of the propeller-blade-

reversing mechanism and shows the propeller blades in flying position, as in Fig. 1.

Fig. 4 is a perspective view showing the propeller-blade carrier fixed to the shaft, the carrier and shaft being detached.

Fig. 5 is a top plan view of the propeller-blade-reversing mechanism, showing a detail of the connection of the shifter with a rack-frame, and shows the rack frame in its forward position in which the propeller blades, not shown, are in position to send the blade wash rearwards for flying. This view is partially in section at line 5—5 of Fig. 3.

Fig. 6 is a perspective view showing the propeller-blade-holding gear, detached.

Fig. 7 is a perspective view showing the rack frame forward and the upper blade in position to send the blade wash forward.

Fig. 8 is a perspective view similar to Fig. 1 except that the propeller blades have been turned about 90° on their long axes to send the blade wash forward.

In that form of the invention set forth, 1 is the mid-section of two integral propeller blades 2 of any proper design, of which there are several; *x* indicating the leading and *x'* the trailing edge of each blade. The mid-section 1 may have any suitable cross-sectional shape and the inner lengthwise-extending space 3 of an arcuate propeller-blade-holding gear (Fig. 6) is shaped snugly to fit the mid-section which is clamped in place by lag-screws 4 the heads of which are shown countersunk in the wall of the gear opposite its lengthwise-extending gap. The headless ends of the screws are provided with nuts, these ends and the nuts being within the normal circumference of the exteriorly round body of such gear, each end of which is provided with an integral projecting arcuate gear 5, and the intermediate exteriorly round and smooth bearing wall of which is indicated by 6. Thus the propeller blades are provided at their mid-section with a blade-holding gear which is rockable in a propeller carrier comprising a half-round bearing 7 fixed on the end of the motor shaft 8, the bearing 7 having projecting flanges 9 which match and are clamped to the corresponding flanges 9' of a half-round supplementary bearing cap 10 by clamp-bolts 11; 100 the bearing 7 and cap 10 enclosing the body portion 6 of the blade-holding gear and the ends of bearing 7 and cap 10 having a sliding

fit on the flanges 5 of such gear. On the motor shaft 8, back of bearing 7, an endwise-slidable rack-frame revoluble with the shaft is mounted and provided, parallel with the motor shaft, with a toothed rack in mesh with each gear-toothed flange 5 of the blade-holding gear. This frame comprises a back plate 12 having on its side towards the motor M an annularly grooved boss 12^a and carrying in outward projection from the plate a pair of fixed U-shaped frames spaced apart in parallelism one with another and having their ends fixed to the plate at 12^b. The heads 16 of these U-frames are shown parallel to the plate 12 and are connected together and braced apart by an interposed strut 17. Each side bar 13 of a U-shaped frame is opposed to the other side bar 14 of that frame; the two side bars 14 of each U-shaped frame are provided with rack teeth 15, each series being in mesh with a flange-gear 5, and the ends of the opposite teeth being slightly engaged by the inward side of a bar 13. The two side bars 13 cooperate with the two rack bars 14 to hold the flanged gears 5 in working position. By moving the rack frame longitudinally in either direction, it is obvious that the blade-holding gear and propeller blades will be rocked in one direction or the other on their long axes.

The present form of such frame shifter under control of an operator in the aeroplane which is partially indicated by A and which is of the usual heavier-than-air type and has non-reversible or fixed planes *a*, comprises a ball-retaining collar 18 for confining anti-friction balls 19 in the annular groove 20 of the back-plate boss 12^a; an endwise movable rack-frame shifter frame having side rods 21 the outward bent ends of which are oppositely secured at 22 to the ball-retaining collar 18. Each rod 21 is slidably mounted in fixed bearings 23 on the side of the motor M, and at the anti-propeller end of the motor the rods are transversely connected one with another by the crosshead 24 at a sufficient distance from the adjacent motor end to permit the shifter frame to be reciprocated.

The shifting movement is preferably accomplished by a hand lever 25 accessible to the operator, the foot of the lever being pivoted at 26 to the aeroplane structure and also being pivoted at 27 between its ends to the crosshead of the shifter frame. A leaf spring 28 having its bottom end fixed at 29 to the aeroplane structure and its free end bearing on the side of the hand lever farthest from the motor, serves during flying to keep the rack-frame and therewith-connected parts in outward positions from the motor, the rack-bars between their ends being then in mesh with the flange gears 5. If now by the mechanism described, the propeller blades are rocked about 90° on their lengthwise axes by a forward movement of the

rack-frame shifter frame, the leading and trailing edges of the blades will be reversed from their flying position shown in Figs. 1 and 3 in which the blade wash is rearwards, into the position shown in Figs. 7 and 8, in which the blade wash will be forward instead of rearwards, thus setting up a counter-force tending to slow down the speed of the aeroplane in its forward travel. The leading edges of the propeller blades 2 and 2^a in their reversed positions are indicated by *x*, and their trailing edges by *x'* in Fig. 8. It is assumed that the propeller, viewed from in front of it is rotating in counter-clockwise direction under all circumstances.

As the aeroplane structure comprises members, not shown, for balancing the aeroplane while the motor is turning, there is a combinative relation at all such times between the aeroplane and our propeller-blade-rocking mechanism and the blades. The rack carrier is preferably kept from turning on the motor shaft by a feather 30^a working in its lengthwise-extending groove 30.

A feature of this invention lies in the described construction whereby the propeller as an entirety is held at all times with its transverse plane, that is with the plane passing transversely through its hub and intersecting the long axes of the propeller blades, perpendicular to the longitudinal axis of the aeroplane so that the reversal of the propeller blades is at all times instantly possible with said planes in such relation to the axis of the aeroplane and consequently with the propeller blades in proper position relatively to the planes for retarding the landing speed by a mere reversal of the blade wash; the planes being at all times in the main and except for warping if any, in a fixed approximately horizontal position relatively to the path of flight. In other words, the planes of our machine are non-reversible and are never tipped so as to stand vertically edgewise.

We are aware of the Bush Patent No. 1,213,585 of January 23, 1917, showing a lighter-than-air aircraft comprising a large vertical gas bag above a pair of reversible wings or planes that form part of a heavier-than-air structure in which the blades of the driving propeller on a horizontal motor shaft are rockable on their long axes, but in which such propeller is carried by a laterally swingable countershaft that is connectible by a clutch mechanism under the control of the operator with both the horizontal motor shaft and also a vertical propeller shaft. The wings or planes of Bush's lighter-than-air machine are not substantially fixed as in heavier-than-air aeroplanes, but are mounted upon the longitudinal axes and movable at the will of the driver, so that they may be arranged in either of two angularly related positions, in one being present-

- ed at right angles to the longitudinal plane of the machine, to avoid air resistance in the direct elevation of the machine, and in the other to be arranged in such longitudinal 5 plane of the machine for use as sustaining members in flight. The adjustment of the planes adapt their use for air brakes in direct flight, and for air-resisting elements to prevent a too-rapid descent of the machine.
- 10 The driving propeller is designed to be utilized as a rudder, in that it may be deflected to one side or the other at the will of the driver, and also to be utilized as a flight retarding element through provision of 15 means for reversing the blades.
- We disclaim all that is set forth in said Bush patent.
- Having thus set forth one form of our invention and recognizing that our invention 20 may be embodied in other forms,
- What we claim is:
1. The combination of a heavier-than-air aeroplane having a non-reversible laterally-extending plane at each side of its fuselage; 25 a motor and its shaft carried by the aeroplane; a bladed propeller mounted on and revoluble with the motor shaft, the blades of the propeller being rockable on their lengthwise axes; and a mechanism under the control of the operator and constructed and operating to hold the rockable blades in position to cut through the air and during normal forward flight to direct the blade wash in a direction opposed to the direction of such 30 flight, and also, at the will of the operator, to rock the blades on their said axes during forward flight in landing movements, and then and thereby set up a counter force operative to slow down the said travel of the 35 aeroplane; the planes and blades cooperat- 40 ing to support the aeroplane in the air and to keep it from sinking vertically in the air when the blades are rotating; all cooperating to enable the operator to slow down and subject the aeroplane to a counter-opposing 45 force of air over and at the landing place.
  2. In the combination set forth in claim 1, a propeller-carrier mounted on the motor shaft, and a propeller-blade-holder rockable in the carrier, the aforesaid mechanism under the control of the operator and constructed and operating to hold the rockable blades in position to cut through the air and during normal forward flight to direct the blade wash in a direction opposed to the direction 50 of such flight and also at the will of the operator to rock the blades on said axes during forward flight in landing movements, and then and thereby set up a counter force operative to slow down the forward travel 55 of the aeroplane, comprising means for rocking the holder; and shifting means under the control of the operator.
  3. The combination of a heavier-than-air aeroplane having non-reversible planes, a 60 motor, and motor shaft provided with a propeller carrier; a propeller-blade-holding gear rockable in the carrier; a propeller blade fixed in said gear; a rack-carrier revoluble with and slidable on the shaft and 65 having a rack in mesh with said gear; and means for shifting the rack-carrier to rock the gear and thereby rock the propeller blades on their long axes, the bladed propeller having a fixed plane of rotation that 70 is substantially perpendicular to the longitudinal axis of the aeroplane.

In testimony whereof we have hereunto set our hands this 18th day of January, 1919.

AUBREY LEO McCAFFREY.
JAMES G. MANNING.
